UNITED STATES PATENT OFFICE.

DAVID LAIRD, OF FORFAR, SCOTLAND.

RETORT-FURNACE.

SPECIFICATION forming part of Letters Patent No. 696,456, dated April 1, 1902.

Application filed September 24, 1901. Serial No. 76,827. (No model.)

To all whom it may concern:

Be it known that I, DAVID LAIRD, engineer and metallurgist, a subject of the King of Great Britain and Ireland, and a resident of 5 Forfar, in the county of Forfar, Scotland, have invented a certain new and useful Improved Retort-Furnace, of which the following is a specification.

This invention relates to retort-furnaces 10 used for retorting amalgams in the process of separating precious metals from their ores.

My invention particularly relates to the 15 construction of a furnace in which means are provided for the more uniform heating of the retort to prevent local burning and for supporting the retort on a solid base practically throughout its length instead of at each end only, as in present practice.

20 In the accompanying sheet of drawings, Figure 1 shows the improved furnace in sectional elevation. Fig. 2 is a plan thereof. Fig. 3 is an end view, and Figs. 4 to 8 detail views.

25 In carrying my invention into effect I provide a dome-shaped body of fire-clay *a*, enveloped in a thin sheet-steel casing *b*, bound with hoops *c* and having metallic end plates *d*, which may be suitably bolted together or 30 secured to the body *a* of the furnace. The furnace *a* is formed with a chamber *e*, at the bottom of which I arrange slabs *f*, of fire-clay, which form a bed or support for the retort *g*. Below the fire-clay bed *f* of the 35 retort is a flame-bed *h*, which communicates, by means of branch passages *i*, with the spaces left at the sides and roof of the retort *g* in the chamber *e*. This arrangement is shown in cross-section in Fig. 4, the section being 40 taken on the line A B, Fig. 1. The retort is connected at *j* with the usual or a suitable condenser *k* and is closed by means of a door *l*. A second door *m*, hinged at *o* to one of the 45 end plates, is provided, which door is secured by means of swing-bolts *p*, pivoted to lugs *q*, carried by the end plate *d*, engaging with slots formed in lugs *r* on the door. (See Figs. 5 and 6.) To open the door, the nuts *s* are slackened and the swing-bolts *p* disengaged 50 from the slots in the lugs *r* on the door, as will be understood. The door *l* of the retort is provided with a packing of asbestos to

form a gas-tight joint with the retort. This door *l* is secured in a manner similar to the door *m*, as will be seen from an inspection of 55 Figs. 7 and 8; but the door is not hinged, but removed bodily. In case difficulty is experienced in effecting this the door *l* is provided with tapped lugst. Screwed rods *u* are brought into engagement with the lugs *t*, the rods 60 passing through the bored-out lugs *u'* on the flange of the retort *g* and bearing against the end plate *d* of the furnace. By rotating the screwed rods *d* the door *l* is screwed upon the rods and is thus forced off the retort. 65

To heat the retort, I provide a burner consisting of an air-blast nozzle *v* and liquid hydrocarbon drip-nozzle *w*. A flame of intense heat is produced and projected within the flame-bed *h* of the furnace by the pressure 70 of air, which may be obtained from any suitable source. Instead of liquid hydrocarbon, hydrogen gas may be employed. The heat thus generated is imparted to the fire-clay bed *f* of the retort, which serves not only to 75 support the retort practically throughout its length, but radiates and distributes the heat more effectually and prevents local burning of the retort at the point nearest the flame of the burner. The cross-passages *i* conduct 80 the heated gases to the sides and roof of the chamber *e*, so that the heat is quickly generated to decompose the amalgam, the volatilized mercury passing through the outlet *x* of the retort to the condenser *k*. In order 85 to still further regulate the heat of the furnace and insure as much as possible the uniform heating of the retort *g*, the chamber *e* and furnace-bed *h* are inclined toward the retort in the direction farthest from the burner 90 to concentrate the heat. Further to assist this the bed *f* of fire-clay terminates before the end of the flame-bed *h* is reached, so that the hot gases may come into direct contact with the base of the retort. 95

A sight-hole *z* is provided at one or it might be at both sides of the furnace-body *a* to afford means for inspecting the interior of the furnace.

I declare that what I claim is—

1. In combination in a retort-furnace, a retort *g*, a dome *a* of fire-clay in which the retort is placed, said dome having below the retort an inclined flame-passage *h*, and around

the sides and upper part of the retort a space *e* tapering toward the end of the retort, lateral passages *i* communicating between the flame-passage *h* and the space *e*, a fire-clay bed *f* below the retort upon which the same rests, said fire-clay bed being supported by the dome *a*, and a burner *v w* for liquid hydrocarbon or gas, and air under pressure, substantially as described.

10 2. In combination in a retort-furnace, a retort *g*, a door *l* leading into retort, and a condenser *k*, a dome *a* of fire-clay in which the retort is placed, end plates *d* and door *m* pro-

viding access to the retort, an inclined flame-passage below retort, a space *e* around the 15 sides and upper part of the retort, lateral passages *i* communicating between the flame-passage *h* and the space *e*, a fire-clay bed *f* below the retort upon which the same rests and a burner *v w*, substantially as described. 20

In witness whereof I have hereunto set my hand in presence of two witnesses.

DAVID LAIRD.
